US00D901482S

(12) **United States Design Patent** (10) **Patent No.:** **US D901,482 S**
Koo (45) **Date of Patent:** **** Nov. 10, 2020**

(54) **STAND FOR ELECTRONIC COMMUNICATIONS DEVICE**

(71) Applicant: **SPIGEN KOREA CO., LTD.**, Seoul (KR)

(72) Inventor: **Bonyoung Koo**, Seoul (KR)

(73) Assignee: **Spigen Korea CO., LTD.**, Seoul (KR)

(**) Term: **15 Years**

(21) Appl. No.: **29/728,621**

(22) Filed: **Mar. 19, 2020**

(51) LOC (12) Cl. **14-03**

(52) U.S. Cl.

USPC **D14/253**

(58) **Field of Classification Search**

USPC D14/251-253, 447, 452, 432-434, 440;

D12/415; D3/218

CPC H04M 1/02; H04M 1/04; B60R 11/02;

F16M 11/00; F16M 11/04; F16M 11/06

(57) **CLAIM**

The ornamental design for a stand for electronic communications device, as shown and described.

DESCRIPTION

FIG. 1 is a front perspective view of a stand for electronic communications device showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines throughout the drawing figures depict portions of the stand for electronic communications device that form no part of the claimed design.

1 Claim, 8 Drawing Sheets
